UNITED STATES PATENT OFFICE.

EDWIN R. ELLSWORTH, OF BROOKLYN, NEW YORK.

APPARATUS FOR MAKING GAS FROM OIL AND STEAM.

SPECIFICATION forming part of Letters Patent No. 438,071, dated October 7, 1890.

Application filed March 31, 1890. Serial No. 346,091. (No model.)

To all whom it may concern:

Be it known that I, EDWIN R. ELLSWORTH, of Brooklyn, in the county of Kings and State of New York, have invented a new and useful

5 Improvement in Apparatus for Making Gas from Oil and Steam, of which the following is a specification.

10 My invention consists in an improved apparatus for making gas from oil and steam, hereinafter fully described and claimed.

Figure 1 is a vertical section. Figure 2 is a front elevation; Fig. 3, a rear elevation. Fig. 4 is a longitudinal section through the atomizer. Fig. 5 is an elevation of the gages ordinarily used in this class of work. Fig. 6 is a front elevation of the oil-valve, and Fig. 7 is a section on line 7 7, Fig. 1.

15 A represents a wall of masonry inclosing the apparatus, the rear upper part being usually made slanting, as shown at *c*, and wholly or partially movable. This part may be made of metal, tile, or other suitable material supported on uprights *e'*.

20 C represents a fire-place between the wall A and the bridge-wall B, having a fire-door N and an ash-pit door N'.

Y represents a coil of pipe for superheating steam, the size of which is of course proportioned to the size of the apparatus, and it may 25 be either a naked pipe or may be protected by being partly or wholly cast in a metal shield Y'. This coil is located in the fire-place C, to be heated by the flame and products of combustion therefrom.

30 D represents another fire-place, usually smaller than C, on the other side of bridge-wall B, and provided with a fire-door P and an ash-pit door P'.

35 E represents a retort extending forward and upward across the apparatus, the rear end being directly over the fire-place D and the other end extending above fire-place C, as shown in Fig. 1. The top *m* of the retort is preferably made in a series of levels, each provided with a man-hole and plate *e*, while the bottom is formed with steam-passages K therein, and preferably in a series of curves, as shown in Fig. 1, though it may be straight.

O' represents a removable plate bolted to the front of retort E, to which the sprayer O 50 is bolted by means of the projecting disk *n*, formed on said sprayer.

i represents a perforated or slotted plate extending vertically across retort E, thus forming a chamber I, into which the spray of oil 55 and steam is thrown, and which passes through the perforated plate *i* into the retort.

R R represent gas-pipes leading from the top of the retort E to the places where the gas is to be used.

60 X represents gages to indicate the pressure in the different oil and steam pipes leading to the apparatus and the gas-pressure in the different retorts, for I usually put several sets of retorts in one apparatus, though of course 65 this is optional.

X' represents a gage showing the opening of the valve controlling an oil pipe or pipes.

M represents an oil-pipe leading from any convenient source of supply to the atomizer O. 70

Z represents a steam-pump for forcing the oil through pipe M into the atomizer.

S represents a flue to lead the products of combustion from the furnaces to a stack. I prefer the arrangement shown with two fire- 75 places or furnaces C and D, because this permits the superheating-coil Y to be heated to a high temperature without raising the lower part of the retort to a temperature so high as to produce gas-carbon therein, and the sec- 80 ond furnace D permits the lower end of the retorts to be separately heated to a tempera- 85 ture designed for working the apparatus; but of course the apparatus may be used with only a single furnace, if desired, in which case the bridge-wall B would be so proportioned as to permit the heat from furnace C to strike the retort at a somewhat lower point than shown in the drawings.

The ends of the coil Y (or of each coil) connect with a branch pipe Q, which is connected with a header K' in front of each retort.

90 K represents pipes (one, two, or more to each retort) which lead from the header K' 95 to the atomizer O, forming steam-passages in

the bottom of the retort, by which the temperature of the retort is equalized, the steam in passages K taking up heat if the fire becomes too hot, and giving out heat if the retort cools.

5 The atomizer O consists of a hollow body of metal having an enlarged chamber R², with tapering end R'.

T represents a plug sliding steam-tight through the two stuffing-boxes u u, having a tapering end, and having a central bore t, which opens through the wall of the plug, as shown in Fig. 4. Steam enters the chamber R through pipe K, and oil enters the bore t of plug T through pipe M.

10 V represents a pivoted lever, by which plug T may be moved to vary the annular opening between it and chamber R².

W represents a frame, in which lever V is pivoted, and W' represents a scale, by means of which and the pointer v on lever V the operator can determine the position of plug T. Of course there must be a loose connection between lever V and plug T, or else the frame W must swing.

15 The operation of my invention is as follows: Fires are built in the furnaces or fire-places C and D, and steam from a boiler is admitted to coil Y. This steam becomes superheated and passes through the pipe K to the atomizer O, where it meets a stream of oil coming under pressure through the pipe M and blows the oil in the form of a fine spray into the chamber I against the perforated or slotted 20 plate i, by which it is broken up and more thoroughly mixed with the superheated steam and converted into gas. The gas then passes through the perforated or slotted plate i into the retort E, whence it is let through the pipes 25 R to the places where it is used. By means of the slotted or perforated plate i the oil is split or cracked up thoroughly and forms a better gas than where the oil is atomized directly into a large retort.

30 In the operation the fire in the furnace or fire-place D is regulated so as to heat the retort to such a temperature as will facilitate the conversion of oil into gas without the

danger of producing gas-carbon or lamp-black, and the retort is protected from the intense 50 heat of furnace or fire-place C by the intervening superheating-coil Y and by the steam-passages K.

I have shown three retorts in a single apparatus, the object of this being to prevent 55 stoppage of the apparatus by accident to one retort, and also to permit making different grades of gas at the same time for use in different furnaces. I prefer to separate the different retorts by brick walls rising between 60 them, so that one retort can be cleaned while the next is running, or so that the different retorts may be run at different temperatures at the same time.

What I claim as my invention, and desire 65 to secure by Letters Patent, is—

1. In an apparatus for making gas from oil and steam, the combination of an inclined retort formed with a series of levels, each having a man-hole, a fire-place beneath each end 70 of said retort, and an intermediate coil of steam-superheating pipe, substantially as described.

2. In an apparatus for making gas from oil and steam, the combination of the inclined retort formed with a series of levels and having steam-passages in the bottom, a fire-place beneath each end of said retort, and an intermediate coil of steam-superheating pipe communicating with the steam-passages of the retort, substantially as described.

3. In an apparatus for making gas from oil and steam, the combination of an inclined retort E, formed with a series of levels and having a chamber I at one end and gas-exit pipes 85 R at the other end, an atomizer O, communicating with the chamber I and provided with oil and steam inlet pipes, the fire-places C and D beneath the retort, and the intermediate coil of steam-superheating pipe Y, substantially as described.

EDWIN R. ELLSWORTH.
